DENTAL INSTRUMENT

Luther Lawrence Bosworth, San Diego, Calif.

Application June 28, 1935, Serial No. 28,907

6 Claims. (Cl. 32—46)

This invention relates to a dental ossisector, the primary use of which is to remove bony structure overlying impacted teeth preparatory to extracting them.

5 To the dental profession the problem of impacted teeth is intensely interesting and of great importance. Heretofore only three methods have been employed in the removal of such teeth; (1) the chisel and mallet, (2) the surgical drills; and (3) the hand pressure cutting instruments.

10 Progress in dental surgery depends as much upon improving the instruments employed as upon improved technique. There has long been 15 felt a need for improving present instruments in such a manner as to make it possible to cut bone with less pressure, less exertion, and less traumatization of tissue. Also to shorten the time required for operations thus lessening the shock to the patient.

20 By this invention an instrument is provided whereby an improved and radically different method of operating upon impacted teeth is rendered possible, but the use of the invention is by 25 no means confined to impacted teeth. Instruments constructed according to the principles of this invention are applicable anywhere in the mouth, and when badly curved or exostosed roots are found the tooth can be removed intact after 30 these instruments have been used to remove the obstructing tissues. Among the objects attained and advantages secured by the use of the instrument furnished by this invention may be mentioned the following: Local anaesthesia may be 35 used for all types of impactions; a safer control of instruments is ensured; the operator can see the field of operation at all times; bony tissue can be more easily removed; very little pressure is required when cutting away the bony structure; less cutting is necessary; ease of operation results with less shock to the patient; there is less trauma and a more rapid recovery; and there is afforded to the operator greater ease and dispatch in the removal of impacted teeth.

40 45 Other objects, advantages and features of invention may hereinafter appear.

Referring to the accompanying drawing, which illustrates what is at present deemed to be a preferred embodiment of the invention,

50 Fig. 1 is a perspective view of the complete instrument.

Fig. 2 is a transverse section, on an enlarged scale, thru the applicator portion thereof, on line 2—2 of Fig. 1.

55 Fig. 3 is a vertical section of the applicator

portion, the plane of section being indicated by the line 3—3 on Fig. 2.

Fig. 4 is a side elevation illustrating the position of one of the instruments in an operative situation within the mouth of a patient, the root 5 of the tooth being operated upon and those of adjacent teeth being shown in dotted lines, another of the instruments being similarly shown in readiness to perform the second stage of the 10 operation.

Fig. 5 is a view like Fig. 4 except that other types of instruments, constructed according to the principles of the invention are illustrated and positioned for different cutting operations.

Fig. 6 is a side elevation outlining diagrammatically the applicator portions of a set of instruments differing in design but all constructed in accordance with the invention.

Referring in detail to the drawing, the applicator portion 5 of the instrument designed as 20 shown in Figs. 1, 2 and 3 is of a somewhat wedge-shaped character and has, extending lengthwise of its face a plurality of longitudinal, angular cutting ridges or blades. By preference and as 25 shown, these cutters consist of a prominent central cutter 6, and outer cutter 7 at each side and a cutter 8 at each side between an outer cutter 7 and the central tooth 6.

The applicator portion 5 is joined by means of an offset neck 11 to a diametrically reduced 30 portion 12 of the tool shank 13, there preferably being a definite annular shoulder 14 between the shank portions 12 and 13. A transversely extending handle 15 having a fluted central portion 16 is secured to the outer end of the shank 13. 35

Describing more in detail the applicator or cutting portion 5 of the instrument, said portion, as viewed in transverse section, is somewhat convex and preferably smooth along its back side 17, and its opposite side or face is of a serrated, generally 40 convex shape, the side portions being chamfered or flattened at 18. Owing to the downwardly tapering character of the cutting portion 5, each of the five angular cutting ridges thereof, which operates as a knife upon the bone with a shearing 45 action, diminishes downwardly in its cross sectional extent. The central cutting ridge 6 is shown as substantially right angled in cross section, tho a greater or less degree of angularity could be used without departing from the spirit 50 of the claimed invention. The cutter ridges 7 and 8 at each side of the center each have their faces disposed to each other at less than a right angle as viewed in cross section, and perform their cutting or shearing action when the tool 55

is rocked as indicated by the arrows above Fig. 2. That is to say, the right hand cutters 7 and 8 cut when the tool is rocked towards the left, and the corresponding left hand cutters act when the 5 tool is rocked in the opposite direction.

- Fig. 4 shows the operative relation of the instrument in relation to an impacted molar tooth 20 to remove the obstructing portion of the bony structure at one side of the crown of the offend 10 ing tooth to permit the proper application of an elevator thereto. In removing the bony tissue as stated the instrument is operated by a rocking movement during which its cutting surface may be either directed away from or toward the tooth 15 to be elevated, while its smooth back surface is always directed towards the adjacent tooth. This manner of operating the instrument prevents the tooth not being removed from having its enamel injured.
- 20 The various cutting ridges of the instrument are bone knives with their cutting edges arranged to operate in both directions so as to produce the greatest cutting efficiency. The bone is cut or sheared from three surfaces, right, left and in 25 front when either a right or left motion is employed, the rocking movement usually being thru an angle of ninety degrees.

In Fig. 5 the letter *b* designates the type of instrument used at the beginning of an excavating operation, and *d* shows the position of another instrument substituted for the first in order that this operation may be satisfactorily completed, thereby providing a clearance above and behind the impacted molar, so that it can be 35 raised and extracted.

Altho the invention is illustrated in the drawing in an operative relation to impacted teeth, yet it is to be understood that it has a wide range of use in other situations for cutting bone when 40 bone surgery is indicated.

45 In Fig. 6 is shown a representative set of instruments constructed according to the principles of the invention. These instruments are lettered, from left to right, *a*, *b*, *c*, *d*, *e* and *a'*, the instruments *a* and *a'* differing from each other only in that one is for right, and the other for left hand use. Figs. 4 and 5 illustrate the use of instruments *a'*, *b*, *d* and *e*. The instrument shown in Figs. 1, 2 and 3 is of a still different design.

50 In Fig. 6 the letter *v* is applied to the applicator portion of each instrument to designate the toothed or cutting face thereof.

So long as the general shape and arrangement of the cutting or shearing elements remain within 55 the scope of the appended claims, various details thereof may be changed, as skilled workmen may desire, without departing from the spirit of the invention.

I claim:

- 60 1. An instrument of the kind described having an applicator portion which tapers from one end to the other, and a shank joining the larger end of said applicator portion, there being a set of

oppositely disposed inwardly directed converging cutting ridges occupying one side or face of said applicator portion which extend lengthwise thereof and progressively diminish in their cross sectional extent away from that end of the applicator 5 portion which is joined to the aforesaid shank, the face of said applicator portion which is occupied by said cutting ridges being of a generally convex character as viewed in cross section.

2. A tool of the kind described having an applicator portion with outwardly convexed opposite faces and a set of converging cutter ridges extending longitudinally of one of said faces, the cutter edges at each side of the medial portion of said applicator portion being directed toward the mid- 15 width thereof.

3. A tool of the kind described having an applicator portion with convexed opposite faces and a plurality of angular cutter ridges or blades extending lengthwise and slantingly of one of said faces, there being a central cutting ridge which runs longitudinally of the axis of the tool and projects farther than the others, and the slanting cutters at each side of said central cutter substantially converging to a point and having their 25 cutting edges directed towards said central cutter.

4. In an instrument of the kind described, an applicator portion having two oppositely disposed faces each of a convex character, said instrument having a shank portion united to one end of said 30 applicator portion, that end of said applicator portion being the largest and said applicator portion tapering toward its opposite or outer end, and there being a set of correspondingly tapering bone cutting knives or ridges extending length- 35 wise of one of said convex faces, said knives including a relatively large central knife which shears when the tool is rocked towards either side and cutting knives at each side thereof whose cutting edges are directed towards said central 40 knife.

5. A tool of the kind described, said tool having an applicator or cutting portion comprising two oppositely disposed faces each of which converge toward a common point, one of said faces constituting a front face and the other constituting a rear face, each of said faces being of a convex character with the rear face of less convexity than said front face, said front face having a plurality of converging cutters at each side of the medial 45 portion of said applicator which are directed toward the mid-width of the tool.

6. In an instrument of the kind described, an applicator portion having two oppositely disposed faces of diverse convexities, said instrument 55 having a shank portion united to one end of said applicator portion, that end of said applicator portion being the largest and said applicator portion tapering towards its opposite end, and a plurality of correspondingly tapering inwardly 60 directed knives on one of said faces.

LUTHER LAWRENCE BOSWORTH.
